SCRAP TOBACCO FEED

James P. Durning, St. Albans, N. Y., assignor to
International Cigar Machinery Company, a
corporation of New Jersey

Application August 19, 1939, Serial No. 291,018

14 Claims. (Cl. 131—22)

This invention relates to cigar machines, and more particularly to improved mechanism for feeding tobacco to cigar forming instrumentalities.

It is an object of this invention to provide a simplified mechanism for feeding short filler tobacco wherein a quantity of short filler tobacco is confined within a limited area and gradually moved forward against relatively movable members which separate the tobacco from the mass confined.

It is a further object of the invention to provide a tobacco feeding hopper having a movable bottom supporting member for a mass of tobacco confined therein together with means for moving said bottom portion to advance the mass of tobacco against rakes which effectively separate portions of the tobacco from the mass for formation into cigar bunches.

It is a further object of the invention to provide a hopper having a traveling conveyor belt forming the bottom part thereof upon which tobacco is confined and moved out of the hopper against a pair of relatively movable members which separate bunch charges of tobacco from the mass.

With these and other objects not specifically mentioned in view, the invention consists in certain combinations and constructions which will be hereinafter fully described, and then specifically set forth in the claims hereunto appended.

In the accompanying drawings which form a part of this specification and wherein the several reference characters designate the same or like elements:

Figure 1 is a partial side sectional elevation of the machine;

Figure 2 is a partial sectional front elevation of the same taken from line 2—2 of Figure 1;

Figure 3 is a sectional plan view of the rake and belt control;

Figure 4 is a sectional side elevation of a modified tobacco feed hopper;

Figure 5 is a sectional front elevation of the lower portion of the same;

Figure 6 is a diagrammatic view of a part of the tobacco feed control mechanism; and

Figure 7 is a partial sectional side view of the mechanism shown in Figure 3.

Referring to Figures 1 and 2, a pair of uprights 10 and 11 extend upwardly from the bed plate of the machine (not shown) and have suitably affixed thereto or formed integrally therewith a brackets 12 and 13, respectively, which carry a tobacco supply hopper 14 and may consist of a

rear wall and side walls terminating in a spout 34. The bottom of the hopper (shown in Figures 1 and 2) is made up of a suitable tobacco supporting surface 19, which as illustrated, is an endless conveyor so mounted with respect to the hopper that its upper lap forms the bottom thereof and travels over a support plate 180 spaced between the drums 17 and 18 which are rotatably supported by cross shafts 15 and 16, respectively, carried by brackets 12 and 13. Other suitable forms also might be employed.

Tobacco in hopper 14 rests upon the traveling surface of the conveyor and is moved forwardly towards rakes or fingers 20 mounted at the discharge end of the hopper, which rakes are usually so positioned that the ends of the rakes are located substantially at the point of tangency of the drum 18 of the conveyor or below the upper lap of the conveyor 18. In this manner, as the tobacco is moved forwardly against the rakes it is practically impossible for any tobacco to slide or move beneath the ends of the rakes 20, and consequently all of the tobacco must move through the rakes. Due to this arrangement, lumps or balls of tobacco are effectively broken up and the tobacco fed in a uniform stream into the bunch forming mechanism will be in the form of loose particles best adapted for the formation of cigars. The rakes 20 are mounted for movement relative to each other, and relative to the conveyor 19. In the embodiment shown they are mounted in bars 25 and 26 pivotally supported for movement, one relative to the other, on a stud 24 suitably supported in a housing or cross piece 21 mounted on brackets 22 and 23 secured to the machine. In order to control the feed of tobacco advanced by the conveyor 19 against the rakes 20, they are usually set into motion during the movement of the conveyor 19 so that as the tobacco moves through the rakes it is separated from the face of the general mass confined by the rakes in hopper 14, and allowed to discharge into the weighing device described more fully hereinafter. One form of mechanism suitable for moving bars 25 and 26 is shown in Figure 2 in which bars 25 and 26 are connected to levers 27 and 28, respectively, loosely mounted on a pivot 29 supported by housing 21. The opposite ends of levers 27 and 28 may be provided with cam followers 30 which engage in a cam track 31 of a cam 32 fixed to the upper end of a vertical shaft 33 supported in bearings of bracket 23. In operation, as the rakes 20 oscillate in opposite directions they scrape and separate from the face of the tobacco mass bearing against them, those pieces

which protrude therethrough from the feeding face of the tobacco mass and thereby permit more tobacco to be fed forward for discharge into the measuring mechanism. The action of the double row of rakes is particularly valuable in that it prevents the forming of or passage of lumps of tobacco from the hopper. The lower portions of the rakes, because of their location below the surface of the upper lap of the conveyor 19, also insure the feed of a uniform stream of tobacco to the spout 34 of the hopper 14.

In order to prevent the short filler tobacco from spilling from the rakes 20 while loading the hopper 14, and to more accurately control the passage of tobacco from the hopper, a row of shorter rakes 35 may be provided. These rakes may be attached to one or both of the bars, but in the illustrated embodiment are shown attached only to the bar 26. These short rakes 35 also control the height of the feeding face of the tobacco adjacent the rakes. Rakes 35 are adjustably fixed in their supporting member in order to best suit them for feeding the type of short filler tobacco being used at a given time, and this adjustable control of the feeding face of the tobacco is important since it permits the use of the mechanism shown and described in feeding any size of short filler tobacco and still retains the desirable feature of feeding a thin layer or thin uniform stream of tobacco from the hopper. Any conventional means of adjusting may be used. For instance, rakes 35 may be provided with threads 35a in the manner shown in Liberman Patent No. 1,559,266.

The shaft 33 is provided with a spiral gear 350 meshing with a spiral gear 36 fixed to shaft 16, thereby imparting motion to belt 19. Shaft 33 is driven through a ball clutch 37 (Figure 3) by means of any suitable conventional type of variable speed drive (not shown) enclosed in housing 38, which drive is suitably driven from the main drive of the machine. Ball clutch 37 may be of any suitable conventional design such as the general type shown in Clausen Patent No. 2,259,616.

Ratchet 39 works in conjunction with ball clutch 37 consisting of a housing 37b and an inner member 37c (Figures 3 and 7). Inner member 37c carried by ratchet 39 is keyed to vertical rake operating shaft 33. Housing 37 is keyed to continuously rotating shaft 38a projecting from the variable speed driving housing 38. Housing 37b carries a number of balls 37a, two as shown, which are confined in wedge shaped spaces formed by the cutouts in members 37c and the inner wall of member 37b. Member 37c is also provided with a corresponding number of plungers or pins 37d spring pressed by means of springs 37e into engagement with the balls for the purpose of pressing the balls 37a into the wedge shaped cutouts and thereby effecting a driving engagement between member 37c and housing 37b on shaft 38. Ratchet 39 is provided with a plurality of downwardly projecting fingers or lugs 39a which serve the purpose of holding balls 37a back and prevent their engagement with members 37c and housing 37b whenever a tooth of ratchet 39 is engaged by a pivoted pawl 40, which stops the movement of ratchet 39 and thereby disengages the rake operating shaft 33 from the continuous rotating shaft 38a which stops the motion of rakes 20 and the feed belt 19.

The tobacco issuing from the mouth of the hopper 14 falls into a scale pan 41 pivotally mounted on shaft 42 supported by brackets B.

This mechanism may be of the type shown and described in my co-pending application, Feed for cigar bunch machines, which issued December 29, 1942 as Letters Patent No. 2,306,381. To scale shaft 42 is fastened a lug 43 carrying a threaded rod 44 supporting an adjustable weight 45. The latter serves the double purpose of balancing the scale pan 41 and determining the desired amount of tobacco to trip the same.

As the uniform stream of tobacco forwarded by the hopper enters the scale pan, the latter trips when the desired amount is deposited therein. The scale pan 41 in tripping causes a suitable switch, such as a mercury switch 46 attached to one end of scale shaft 42 to swing into an angular position and thereby break an electric circuit leading to a solenoid 47 which controls the drive of shaft 33, in a manner to be described. Solenoid 47 is energized and deenergized through the circuit being opened and closed by the movement of pan 41 which operates switch 46 through a circuit including wires 100 and 101 connecting switch 46 to solenoid 47 thereby causing the armature 48 of the solenoid to enter or move away from the same thereby engaging or disengaging the pawl and ratchet drive. A bell crank lever 49 mounted on a shaft 50 supported by a bracket 51 connects to the armature 48 and has an arm 52 which will swing and contact a finger 53 of pawl 40 (Figure 3) when the solenoid 47 is energized, thus the pawl will be disengaged from the ratchet 39, permitting ball clutch 37 to be driven from the variable speed drive and impart motion to belt 19 and the oscillating rakes 20. The operation of arm 52 and finger 53 is the same as that described in my copending application, above referred to.

When scale pan 41 is tripped, switch 46 breaks the circuit to solenoid 47 so that the latter is de-energized, and armature 48 will disengage arm 52 from finger 53 of the pawl. Since the latter is equipped with a tension spring 54, said pawl will immediately engage ratchet 39 causing ball clutch 37 on shaft 33 to disengage the latter from the variable speed drive and thereby stop the motion of belt 19 and rakes 20.

When scale pan 41 is tripped, the measured amount of tobacco therein is delivered into a compression chamber similar to that shown in Patent No. 2,021,652, for Scrap bunch machine, granted November 19, 1935, to J. F. Halstead, via a guide chute 56 whenever magazine gate 51 mounted on shaft 65 is open. As the gate swings downward the tobacco charge is evenly distributed and guided into the magazine. A reciprocating plunger 58 will then press the charge and advance the forward end into a transfer 59, which after the charge is separated by means of a knife 60 from the remaining tobacco column in the magazine, will deliver the cut charge to the rolling apron of the machine (not shown). In order to control the feed of tobacco from scale pan 41 into chamber 55, the pan is provided with a prong 66. As the gate 51 swings up to open position it strikes prong 66 and moves the pan 41 about its pivot to effect the discharge of the tobacco held therein into the chamber 55. As the gate 51 swings back into chamber closing position, pan 41 also travels back and is again located to receive tobacco from the hopper. Due to weight 45, the switch 46 is moved to close the circuit and tobacco is fed into the pan until a predetermined quantity causes it to swing in a clockwise direction to break the circuit and discontinue the feed of tobacco thereto. When there

is little or no tobacco in the chamber 55, the plunger 58 during its forward stroke, can move substantially the entire length of the magazine (see Figure 6), and a stud 67 carried by plunger operating arm 68 will trip control lever 69 standing in the path of the stud 67 since the latter is mounted in a block carried by lever 68. The trip of control lever 69 will cause the disengagement of latch lug 71 from latch 72 mounted on trip lever 73 and thereby due to weight 74 cause the trip lever to swing in such a way that follower 75 on arm 76 strikes lock finger 77 mounted on arm 83 and swings it about its pivot 78 to such a position that the recess 79 in the finger is located directly beneath the crank pin 80 which is mounted in the free end of lever 81 pivoted to a shaft 82 and adapted to engage a slot 80a of arm 83. The arm 83, through its cam lever 84 and connecting rod 85 moves up and down once each cycle of the machine due to the engagement of cam follower 86 on a cam 86 mounted on shaft 87. With the parts in the positions, just described above, as the arm moves upward again during the next cycle of the machine, recess 79 will engage with and seat crank pin 80 therein, thereby preventing relative movement of pin 80 in slot 80a, and upon continued upward movement lever 81 on shaft 82 will be moved upward thereby effecting the movement of lever 88 mounted on shaft 82 and connected by connecting rod 89 to lever 90 fixed upon shaft 66 so that this movement rocks the magazine gate 51 to open the magazine 55, and when the gate engages prong 66 causes the discharge of tobacco into the chamber 55. Latch lug 71 is provided with a curved face 71a upon which latch 72 travels whenever lever 69 is moved to break the latching engagement between lug 71 and latch 72. The latch mechanism is reset by means of arm 83 which as it rises causes arm 77 to bear against cam follower 75 on arm 76 and to swing latch 72 upward on curved face 71a to latching position, where by means of weight 88a forming a part of trip lever 69 lug 71 is positioned for reengagement by latch 72 as shown in Figure 6.

If a sufficient quantity of tobacco is present in the chamber 55, stud 67 can not strike trip lever 69, follower 91 on arm 92 swings lever 77 on its pivot out of the path of crank pin 80, slot 80a allows arm 83 to move past pin 80 and thereby prevents gate 51 from being opened during that particular cycle of the machine and so long as sufficient quantity of tobacco is present in the compression chamber. Whenever there is a sufficient quantity of tobacco in magazine 55, lever 77 occupies the dotted line position shown in Figure 6. The mechanism for operating the gate 51 for controlling the feed of tobacco from scale pan 41 thereinto may be substantially the same as that shown and described in my above referred to co-pending application.

In Figures 4 and 5 I have shown a modified form of tobacco feeding mechanism. According to this modification, hopper 61 is provided with an inclined base 62 which is so constructed and arranged that it will direct the tobacco placed therein downwardly against the rakes 20 and maintain the face of the tobacco in the hopper constantly in engagement with the rakes 20 which may be operated and controlled in the same manner as those in the modification shown in Figures 1 and 2. Since the tobacco is held by gravity against the rakes 20, whenever they are oscillated, the net result is to allow the to-

bacco to move through the rakes in a uniform stream for delivery through the mouth 63 of the hopper 61 and into the scale pan 41. In order to prevent tobacco particles from working beneath the ends of the rakes 20, they are located in close proximity to the wall 64, which forms a continuation of the bottom 62, and are so placed with respect to the bottom 62 that all tobacco fed from the hopper must move through the rakes.

The invention above described may be varied in construction within the scope of the claims, for the particular device, selected to illustrate the invention, is but one of many possible concrete embodiments of the same. It is not, therefore, to be restricted to the precise details of the structure shown and described.

What is claimed is:

1. In a cigar machine tobacco feed, an endless conveyor provided with a horizontal traveling surface supporting a mass of tobacco, a plurality of substantially vertical movable spaced members located adjacent the discharge end of said conveyor confining said mass on said conveyor and having their ends positioned below the supporting plane of said surface, means for moving said conveyor to advance the tobacco on said surface through said members, and means for also moving said members back and forth across the face of the tobacco confined thereby during the advancing movement of said conveyor.

2. In a cigar machine, a hopper for confining a supply of tobacco including, an endless conveyor provided with a traveling tobacco surface forming the bottom of said hopper, spaced rotatable members supporting said conveyor, a plurality of parallel sets of spaced movable rakes located adjacent the discharge end of said conveyor having their ends substantially tangent to the supporting member at the point of discharge of said conveyor confining said tobacco in said hopper, and means for effecting relative movement between said conveyor and sets of rakes to control the quantity of tobacco fed from said hopper.

3. In a cigar machine tobacco feed, an endless conveyor, movable members located at one end of said conveyor for confining a mass of tobacco on said conveyor, a tobacco weighing device located adjacent said conveyor, a charge receiving chamber positioned beneath said device, and means including driving mechanism for said conveyor set into operation when tobacco in said chamber reaches a predetermined minimum for effecting movement between said conveyor and members for feeding a stream of tobacco into said device.

4. In a cigar machine tobacco feed, an endless conveyor, rakes located at one end of said conveyor for confining a mass of tobacco on said conveyor, a tobacco weighing device located adjacent said conveyor, a charge receiving chamber positioned beneath said device, means including driving devices for said conveyor set into operation when tobacco in said chamber reaches a predetermined minimum for effecting relative movement between said conveyor and members for feeding a stream of tobacco into said device, and means operative when a predetermined quantity of tobacco has been fed into said device for interrupting the operation of said conveyor and members.

5. In a cigar machine having a charge compression chamber, and a tobacco measuring device for feeding measured quantities of tobacco

to said chamber, a conveyor having a traveling horizontal tobacco supporting surface arranged to support a mass of tobacco, a plurality of independently movable normally stationary transverse rakes comprising spaced depending tobacco engaging fingers having their tips positioned below the plane of said surface located adjacent the discharge end of said conveyor constructed and arranged to hold said mass on said surface against uncontrolled movement from said conveyor, means for effecting relative movement between said conveyor and rakes, including mechanism for rocking said rakes back and forth adjacent the end of said conveyor to feed tobacco in a stream to said device, and means controlled by the quantity of tobacco fed to said device for stopping the movement of said conveyor and rakes.

6. In a tobacco feeding device, a stationary hopper provided with end and side walls extending upward from an elongated bottom, a conveyor movable above and closely adjacent said bottom, said conveyor supporting a mass of tobacco in said hopper between said walls and constructed and arranged to advance said tobacco to a point of discharge, a plurality of substantially parallel sets of transversely positioned spaced rakes having spaced tobacco engaging members located at said point of discharge and coacting with said conveyor to hold back said mass of tobacco in said hopper, mechanism for moving said conveyor relative to the walls of said hopper to advance said tobacco confined in said hopper against said rakes, and means for moving said sets of rakes relatively to each other back and forth across the face of the mass of tobacco fed thereagainst by said conveyor to effect the feed of a stream of tobacco from said hopper and between said members.

7. In a tobacco feeding mechanism for a cigar machine, an open hopper adapted to hold a mass of tobacco provided with upstanding spaced side walls and an elongated and downwardly inclined bottom tobacco supporting section arranged to advance the tobacco by gravity extending between said walls and forming an outlet at the lowermost portion of said section, a plurality of substantially vertical rakes, means mounting said rakes in closely adjacent substantially parallel planes, said rakes comprising spaced tobacco engaging fingers located adjacent said outlet, and extending transversely across between said side walls with the ends of said fingers positioned below the plane of said bottom supporting section, said rakes being constructed and arranged to hold back said mass of tobacco on said bottom section against the free gravity feed therefrom, and means for moving said rakes back and forth relative to said walls and section to effect the feed of tobacco from said hopper only between said fingers.

8. In a tobacco feeding mechanism, a hopper including upstanding side walls, and an angularly inclined bottom section arranged to support and advance a mass of tobacco by gravity, a plurality of sets of substantially vertical rakes comprising spaced tobacco engaging fingers having their lower ends located adjacent the lower inclined edge and below the plane of said section and extending transversely across said section to hold back said entire mass of tobacco thereon against free gravity feed therefrom, and means for moving said sets of rakes back and forth past each other across the face of said mass of tobacco held back thereby to allow

tobacco to be fed between said fingers from said mass.

5 9. In a material feeding mechanism, a hopper adapted to contain a supply of material, said hopper including an end and side walls and a bottom comprising a substantially horizontal endless movable conveyor for supporting said supply of material located between said walls, said conveyor being constructed and arranged to advance said material to a point of discharge at one end of said conveyor, a plurality of rakes having depending material engaging fingers located at said end of said conveyor, means mounting said rakes to position the ends of said fingers below the plane of said conveyor and at substantially right angles to said conveyor to hold within said hopper said entire supply of material, means for moving said conveyor to advance material against said rakes, and mechanism associated with said last-named means for moving said rakes back and forth past each other to affect the feed of material between said fingers.

10 10. In a cigar machine, a hopper adapted to contain a supply of tobacco, mechanism for feeding a stream of tobacco from said hopper comprising, a conveyor constructed and arranged to form a bottom of said hopper and a support for said tobacco, a plurality of sets of substantially parallel spaced rakes located adjacent the discharge end of said conveyor holding back said supply of tobacco in said hopper, means for moving said conveyor to feed tobacco to said rakes, and means for also moving said rakes past each other back and forth across the face of the tobacco fed thereto by said conveyor to separate tobacco from said supply for delivery between said rakes from said hopper.

15 11. In a charge forming device for a cigar machine having a charge compression chamber, a device for measuring tobacco, and a chute adapted to conduct said measured tobacco from said device into said chamber, a hopper for confining a mass of tobacco including a conveyor provided with a substantially horizontal tobacco supporting and conveying surface forming the bottom of said hopper, a plurality of sets of substantially parallel rakes located at the discharge end of said conveyor coacting with said surface and holding back said mass of tobacco in said hopper, means for mounting said rakes in substantially vertical planes and at substantially right angles with said conveyor, interconnected means for simultaneously operating said conveyor to advance tobacco against said rakes and for moving said rakes back and forth adjacent the end of said hopper and said conveyor to feed a stream of tobacco past said rakes to said device, and means controlled by the feed of a predetermined quantity of tobacco to said device for stopping the operation of said conveyor and rakes.

20 12. In a tobacco feeding mechanism, a hopper having side walls, a rear wall joining said side walls, and an inclined stationary bottom portion extending between said walls and terminating in an open discharge end, said bottom portion being adapted to support a mass of tobacco, a plurality of sets of substantially parallel rakes coacting with said hopper to hold back said mass of tobacco in said hopper, means mounting said sets of rakes in substantially vertical planes, exteriorly and transversely of said hopper and closely adjacent said discharge end of said bottom portion to substantially close said opening

and thereby prevent uncontrolled movement of tobacco from said hopper, said rakes depending downwardly relative to said support portion and constructed and arranged to extend below the plane of said portion, and means for moving said rakes in said substantially vertical transverse planes back and forth past each other across the face of the mass of tobacco backed up thereby to allow tobacco to pass between said rakes and from said hopper.

13. In a material feeding mechanism, a hopper provided with side walls, a rear wall, and a bottom material supporting surface associated therewith, said surface extending between said walls and terminating in an open discharge end to confine and support a bulk supply of material, a plurality of sets of substantially parallel rakes coacting with said hopper to hold back said supply of material, means mounting said sets of rakes in substantially vertical planes transversely of the longitudinal axis of said hopper and closely adjacent said discharge end of said surface to substantially close said opening and thereby prevent the flow of material from said supply while said rakes are stationary, said rakes depending downwardly relative to said bottom supporting surface and constructed and arranged to extend below the plane of said surface, and means for moving said rakes in said substantially vertical planes back and forth past each

other across the face of said supply of material supported on said surface to allow material to pass between said rakes and from said hopper.

14. In a material feeding mechanism, a hopper provided with side walls, a rear wall and a bottom material supporting and feeding surface extending between said walls and terminating in an open discharge end for confining and supporting a bulk supply of tobacco, a plurality of sets of substantially parallel rakes coacting with said hopper, said rakes including spaced fingers engaging the advanced face of supply of material to hold back said supply of material in said hopper, means mounting said sets of rakes in substantially vertical planes transversely of the longitudinal axis of said hopper and closely adjacent and exteriorly of said discharge end of said surface with the ends of said fingers extending downwardly below the plane of said surface to substantially close said open discharge end and thereby prevent the flow of material from said supply while said rakes are stationary, and means for moving said rakes in said substantially vertical planes back and forth past each other across the face of said supply of material supported on said surface to allow material to pass between said spaced fingers and from said hopper.

JAMES P. DURNING.

CERTIFICATE OF CORRECTION.

Patent No. 2,329,747.

September 21, 1943.

JAMES P. DURNING.

It is hereby certified that error appears in the printed specification of the above numbered patent requiring correction as follows: Page 3, second column, line 37, claim 2, before "parallel" insert --substantially--; and that the said Letters Patent should be read with this correction therein that the same may conform to the record of the case in the Patent Office.

Signed and sealed this 23rd day of November, A. D. 1943.
